US0D1079030S

(12) **United States Design Patent** (10) **Patent No.:** **US D1,079,030 S**
(45) **Date of Patent:** **** Jun. 10, 2025**

(54) **MUSCLE STIMULATOR**

(71) Applicant: **HAIKOU LILI INVESTMENT CO., LTD.**, Haikou (CN)

(72) Inventor: **Junyu Chen**, Haikou (CN)

(73) Assignee: **HAIKOU LILI INVESTMENT CO., LTD.**, Haikou (CN)

(**) Term: **15 Years**

(21) Appl. No.: **29/926,780**

(22) Filed: **Feb. 1, 2024**

(30) **Foreign Application Priority Data**

Sep. 21, 2023 (CN) 202330619029.8

(51) **LOC (15) Cl.** **24-01**

(52) **U.S. Cl.**

USPC **D24/200**; D24/215

(57) **CLAIM**

The ornamental design for a muscle stimulator as shown and described.

DESCRIPTION

FIG. 1 is a top, front, right perspective view of a muscle stimulator showing my new design;

FIG. 2 is bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the muscle stimulator that form no part of the claimed design.

1 Claim, 8 Drawing Sheets
